UNITED STATES PATENT OFFICE

ARTHUR PEEL, OF LONDON, ENGLAND

INDEXING DEVICE

Application filed August 7, 1930, Serial No. 473,669, and in Great Britain November 1, 1929.

This invention relates to stationery, and has for its object to provide means for operating a visible system of indexing or filing for the purpose of keeping record cards requiring fortuitous alterations or changes in arrangement in a more convenient manner than the usual arrangement of stacking them one behind the other in drawers.

In the system to which the present invention relates, the cards will lie flat, their lower edges being stepped, for example, a quarter of an inch below the edges of preceding cards, all the cards being hingedly connected to detachable fasteners in a manner permitting the ready separation of adjacent cards, the cards being also readily detachable from their hinged holders. Thus, a system of records may readily be kept in which the headings of each record are all clearly in view, any required card being readily separable from the rest for the purpose of adding new particulars or otherwise, and additional intermediate cards being readily insertable in the series in the case of an alphabetical arrangement.

It is intended that the record cards shall be put up, for example, in fifties, and mounted in a folder tray or drawer wherein any given card may be readily examined by lifting up the cards above it, and any given card may be readily detached as above explained.

The invention is applicable to keeping all kinds of data, for example, police records or notes, map sections for aeroplanes, patterns of cloth, or samples of paper, as will be readily understood.

The invention comprises a device for keeping indexing systems as above, the device in one modification comprising a clip holder and a paper or card holding clip hingedly mounted thereon, the clip holder being constructed in such a manner that a plurality of similarly formed clip holders can readily be secured to each other in a continuous series.

In a preferred form, the clip holders are in the form of backings, a backing being formed with oppositely facing lugs serving as half hinge straps, adjacent backings being engaged together by the edge of one plate abutting one or more lugs on the second plate and

being prevented from separation by a wire hinge pin integrally formed at its ends into paper-holding clips and engaging behind the half hinge straps in the assembled backings as will be hereinafter described.

The invention further includes a construction of wire loop shaped to coat with lugs formed at the top edge of a card, envelope, folded sheet or the like whereby the paper may be readily inserted into and withdrawn from the holding device.

The invention will now be more particularly described with reference to the accompanying drawing in which

Fig. 1 is a modified form of backing having lugs to form half hinge straps.

Fig. 2 shows a hinge pin provided with paper-holding clips for use with the backing of Fig. 1.

Fig. 3 is a plan of Fig. 2.

Fig. 4 shows a plurality of backings and clips assembled together.

Fig. 5 is an alternative construction to Figs. 1 to 4.

Figure 6 is a broken perspective view showing the folded paper to be used in connection with the construction illustrated in Figures 2 and 3.

Fig. 1 illustrates an embodiment in which the backing 40 comprises a shaped plate of sheet metal having in the form shown three struck-up lugs 41, 42, 43, designed to serve as half hinge straps, the central lug 41 being bent downwardly and the lateral lugs 42, 43 being positioned on opposite sides of lug 41 and being directed upwardly. The lower edge of the plate 40 is cut away to form a central recess 44 having a plane central upper edge designed to engage and position the central lug 41a of a second backing. When so positioned the lug 41a of the second backing and the lugs 42, 43 of the plate 40 will form oppositely directed half hinge straps which can receive a wire such as that indicated in dotted lines at 45, the wire serving as a hinge pin for a paper holder and also securing the two backings together. In order to preserve alignment of the assembled backings, the plate is extended downwardly at its sides for a greater dis-

tance than the height of the lug 41 above the lugs 42, 43, the bottom edge of the plate being recessed at 45, 46 snugly to receive the lugs 42a, 43a of the backing which carries the lug 41a, and recesses 44a, 45a, 46a.

To complete the assembly I provide a hinge pin shaped as illustrated in Figs. 2 and 3. This comprises a wire 50 which is cranked to provide two offset portions 51, 52, the 10 cranked lengths of which will engage either the edges of lug 41a or the edges of lugs 42, 43 to prevent transverse movement of the wire when set up. The ends of the wire are shaped to form squares or rectangles having 15 their outer sides offset, as shown in plan in Figure 3, to receive ears formed on the tops of cards, papers or envelopes by the provision of horizontal slots such as 28, 29. Preferably, the outer vertical lengths of wire 52, 20 53 are offset to lie in front of the plane of the wire as clearly shown in Fig. 3, the horizontal lengths 54, 55 being oblique to the plane of the wire adjacent the length 52, 53 so as to pass naturally through the slots 25 28, 29 of the card without deforming it. Preferably, also the card is creased as illustrated at 29a so that the lower portion will lie flat instead of being liable to stick up owing to the lift produced by the lower 30 length of wire. The holder here illustrated may be applied to single sheets of paper e. g. 32 cm long which are folded twice, the slots 28, 29 being produced adjacent the double fold. This type of folded paper is illustrated in Figure 6, wherein the paper is folded approximately centrally at a and each half is thereafter folded approximately centrally at b and c, leaving creases, a, b, c. The side edges d, e are then formed with four slots, all 35 40 of which register when the paper is folded along the creases and which cooperate with the transverse edge of the folded sheet to form ears.

Fig. 4 shows a plurality of such backings 45 and card holding devices assembled as part of a series. It will be realized that the central lugs 41, 41a, &c. may be complete eyes 50 permanently carrying the wire hinge pins if desired, since the backings can be separated by lifting the lateral arms of the wire away from the lateral curved lugs 42, 43. The construction illustrated, however, is quite effective and cheaper to manufacture and lends itself to easier separation of the parts.

Fig. 5 shows a modification of Figs. 1 to 4, according to which the wire hinge pin is cranked twice only externally of the lugs 42, 43 which thus prevent lateral dislodgment when the wire lies in the position illustrated 60 in the lower lengths. To meet the case when the wire is rocked into the position illustrated in the upper length, I form a pair of up-standing lugs 60, 61 adjacent the outer edges of the lugs 42, 43 behind which the cranked 65 portions of the wire will be located when they

are clear of the lugs 42, 43 so that lateral dislodgment of the wire is in both cases prevented. The ends of the wire are folded back on themselves as shown to provide loops for holding the ears of cards or envelopes as in the previous modification. In the case of envelopes to hold various data, the loops serve to hold down the flaps of envelopes if squared flaps are utilized having slots 28, 29.

In the forms illustrated in Figs. 1 to 5, 70 adjacent backings are urged together by the hinge pins but held from further approach by the abutment of the lugs with the recesses. This feature, however, is not essential. For example, adjacent backings might be urged 80 apart by the hinge pins if the half hinge straps are set up in opposite directions to those shown, the backings being held together by small bent lugs on a lower edge 85 engaging in holes adjacent an upper edge, hook and eye fashion.

The form of the invention thus includes generally the features (1) that after the backings are engaged together, they are held against displacement by hinge pins, and (2) 90 that when the backings are engaged together, half hinge straps co-operate to hold a hinge pin, since shaped lugs to form half hinge straps are more easily manufactured than complete eyes.

It will be realized with regard to the forms illustrated in Figures 1 and 5 that I provide a backing comprising a plate-like structure having a plurality of lugs 41, 42, 43 struck up from one face thereof; that elements, for example, the middle lug of a second backing 41a and recess 44 and the lateral lugs 42a and 43a coact to locate or position adjacent backings; and that when so located the lugs 42, 43 of one backing and the lug 41a of a second 100 backing are substantially in line for engagement by a hinge pin. It will further be realized that this construction requires that the lower edge of a plate be recessed so that the vertical distance in Figure 7 between lug 41 110 and the edge of the plate within recess 44 shall be equal to the vertical distances between lug 42 and the edge of the plate at 45, and lug 43 and the edge of the plate at 46, these distances being measured in parallel 115 directions.

It will further be realized that in the form shown, the lugs are constructed by stamping tongues from the plate structure and shaping these tongues by bending them out of the plane of the plate, the tongues in the form shown being first bent through a right-angle and provided with overhanging ends.

I claim:—

1. In a paper-filing device, a backing having means for detachable engagement to a similar backing, and further means adapted when two similar backings are engaged to co-operate to provide means to hingedly 125 mount a paper-holding device.

2. For use in a paper-holding device, a backing having means to form an abutment whereby two similar assembled backings may be engaged together, and further means whereby when two such backings are assembled they may be held from separation by the hinge pin of a paper-holding device engaging said further means. 70
3. For use in a paper-holding device, a backing comprising a plate-like structure having a half-hinge strap carried by one face thereof and directed in one direction, and a pair of half-hinge straps in the same face directed in the opposite direction. 75
4. A filing device comprising a plurality of similar backings shaped with elements adapted to locate a pair of similar backings when said elements contact, the backings carrying lugs and being adapted to be held from displacement when so located by hinge pins of paper-holding devices engaged behind said lugs. 80
5. For use in a paper holding device, a backing comprising a plate-like structure, a plurality of lugs carried by one face thereof, elements of said structure to locate a pair of backings when said elements are in contact, said lugs being so positioned that when a pair of similar backings are so located a lug of one backing will be substantially in line with a pair of lugs of the other backing for engagement by a hinge pin. 85
6. A backing as claimed in claim 5, in which said lugs are formed by cutting tongues and shaping them by bending out of the plane of said backing. 90
7. A backing as claimed in claim 5, in which said lugs are formed by cutting tongues and shaping them by bending them substantially at right angles to the plane of the backing and forming them with overhanging ends. 95
8. For use in a paper holding device, a backing comprising a plate-like structure, a pair of lugs carried by a face of said structure adjacent the two side edges thereof respectively, a third lug carried by the same face and arranged centrally thereof, laterally located recesses in an edge of said backing to receive and position the lateral lugs of a second similar backing, and a central cut away recess in the said edge intermediate said lateral recesses, said central recess being deeper than said lateral recesses. 100
9. For use in a paper holding device, a backing formed of a plate of sheet metal, a lug centrally carried by a face of said backing adjacent an upper edge, the opposite edge of said backing being provided with a central recess, a pair of laterally arranged lugs carried by the same face of said backing, said laterally arranged lugs being adjacent the side edges of the backing and below the centrally carried lug, the recessed edge of said plate being so shaped that the distance of 105
- the central lug above the edge of said plate within said recess is equal to the distances taken in parallel directions of said lateral lugs above the lateral portions of said edge. 110
10. For use in a paper-holding device, a folded laminar sheet having slots in its side edges adjacent said fold, said slots being in register when said sheet is folded and coacting with a transverse edge of the folded sheet to form holding ears. 115
11. For use in a paper holding device, a laminar sheet foldable substantially centrally and creased so as to be further foldable substantially centrally of each half portion, the side edges of said sheet being provided with four slots adapted to register when the sheet is folded along said three creases to form ears with an edge of said device as folded for co-operation with a holding device. 120
12. For use in securing two backings together in a paper filing device, a combined securing means and hinge pin comprising a length of wire shaped at its ends to hold ears of a sheet of paper or card and having offset portions intermediate its length, those portions of the wire serving as securing means for the backings being axially in line. 125
13. A wire hinge pin to hold a card and secure a pair of backings together comprising a length of wire shaped to form loops at its ends, the portions of wire extending inwardly from said loops being axially in line and connected at their inner ends to cranked portions, the remote ends of said cranked portions being connected to portions extending generally toward each other and terminating in reversely cranked portions which are united by a portion axially in line with said axially-aligned portions. 130
- In testimony whereof I affix my signature. 135
